United States Patent Office

Des. 215,004

Patented Aug. 19, 1969

215,004

ABACUS

Keiichi Oota, 2257-5 Nagamori Kitaitsukiki,
Gifu Prefecture, Gifu, Japan

Filed Nov. 4, 1968, Ser. No. 14,294

Term of patent 14 years

Int. Cl. D19—08

U.S. Cl. D25—1

Fig. 1 4—

Fig. 2 4—

Fig. 3

Fig. 4

Fig. 5

FIG. 1 is a top plan view of the abacus embodying my new design;

FIG. 2 is a front view thereof;

FIG. 3 is a bottom view thereof;

FIG. 4 is a magnified cross sectional view on line 4—4 of FIG. 1; and

FIG. 5 is a magnified perspective view of top, front and right side of one of the beads on the abacus.

I claim:

The ornamental design for an abacus, as shown.
